UNITED STATES PATENT OFFICE.

LEO REVOR, OF LYON MOUNTAIN, NEW YORK.

ROCK DRILL.

Application filed July 10, 1922. Serial No. 573,875.

The present invention is directed to improvements in pneumatic rock drills, and particularly to that type known as stoping drills.

5 The primary object of the invention is to provide a drill wherein means are provided to automatically cut off the air supply to the pneumatically operated feeding mechanism should the drill steel break during the 10 drilling operation. The breaking of drill steel is a common occurrence, and oftentimes results in injury to the drill runner since the drill will be projected upwardly under the action of the feed bar as soon as the 15 drill steel breaks, which causes the drill runner to lose his footing and control of the drill, and if working on a ledge or in a dangerous location the drill runner will be injured, and often fatally. My invention is 20 therefore directed to means for overcoming these objections and dangers by the installation of an automatically operated cut-off, whereby the main air supply will be cut-off at the instant the drill steel breaks, thereby 25 preventing the feeding mechanism from exerting an upward movement to the drill.

With these and other objects in view, this invention resides in the novel features of construction, formation, combination and arrangement of parts to be hereinafter more fully described, claimed and illustrated in the drawing, in which:—

Figure 1 is a fragmentary side elevation of a drill equipped with the device.

35 Figure 2 is a fragmentary sectional view through the front head.

Figure 3 is a longitudinal sectional view through the valve.

Referring to the drawing, 1 designates 40 the cylinder, and 2 the front head in which is clamped the chuck 3, said chuck having a longitudinal groove 4 formed therein, the purpose of which will appear later. The front head 2 is provided with a chamber 5 in which is located for reciprocating movement the tappet 6 actuated by blows from the hammer 7, said hammer being located in the cylinder, as is usual.

50 Live air is supplied to the cylinder in the usual manner to operate the hammer 7, the flow thereof being controlled by the throttle valve 8 which also controls the passage of air to the feed barrel 9 to extend the feed bar 10 therefrom, as is customary in drills 55 of this type.

The construction thus far described, with

the exception of the groove 4 is well known. The usual throttle valve 8 is rotatably mounted on the head 11 which has its major end provided with a chamber 12, the valve 8 60 being equipped with an annular seat 13, the purpose of which will later appear. Threaded in the head 11, and alined with the valve 8 is a bushing 14, and threaded in said bushing is the branch 15 of the spud 65 16, said spud having connected thereto, in the customary manner the air supply hose 17. A stuffing box 18 is carried by the spud 16, and slidably therein is the stem 19 of the circular head 20, said stem bridging the 70 chamber 21 of the spud 16, and extending axially through the branch 15 thereof. The head 20 has formed integral therewith a valve disk 22, which is separated from the head by an annular groove 23, thereby producing an annular shoulder 24, the purpose 75 of which will appear later.

Encircling the stem 19 is a coil spring 25, one terminal of which bears against the head 20, while the other terminal engages the adjacent end of the stuffing box 18, said spring serving to urge the valve disk towards the seat 13. However, under normal conditions, it is essential that the valve 22 be held unseated that air may flow freely from the 80 throttle valve to the hammer chamber and feed bar barrel. In order to hold the valve 22 unseated, a rod 26 is employed, said rod being slidably engaged in the stuffing box 27 carried by the throttle valve casing 90 28. The lower end of the rod extends into the casing 28 and is adapted to engage the shoulder 24, thereby holding the valve disk unseated, and the spring 25 contracted.

The upper end of the rod 26 terminates in 95 a hook 29, the shank 30 thereof being bent downwardly and parallel to the adjacent portion of the rod, said shank being adapted to lie in the groove 4 formed in the chuck 3, and consequently interiorly of the 100 front head 2. It will be obvious that the lower end of the shank 30 is normally spaced a slight distance vertically from the tappet 6, whereby the tappet may normally reciprocate without contacting with said shank. It 105 will be of course understood that as long as the drill steel is intact, the movement of the tappet will be limited owing to the fact that the bit of the drill steel will engage the bottom of the drill bore, and consequently 110 the tappet will be prevented from moving upwardly a sufficient distance to cause the

lower end of the shank 30 to be engaged by the tappet. However, when the drill steel breaks and resistance thereto is relieved, the tappet will instantly move upwardly a distance to cause it to engage the shank 30, whereupon the rod 26 will slide upwardly until its lower end disengages the shoulder 24, whereupon the valve disk 22, under the action of the spring 25 will be instantly forced inwardly until the valve seats on the seat 13, thereby cutting off the supply of air simultaneously to the feed bar barrel and hammer chamber. Thus it will be seen that the instant the drill steel breaks that the supply of air to the pneumatically operated feeding mechanism will be cut off, thereby preventing the drill from being projected sharply upwardly, as now frequently occurs, with the result that the drill runner is seriously, and possibly fatally injured due to losing his footing in an attempt to control the drill as it moves upwardly under the action of the feeding mechanism.

The head 20 is provided with a plurality of perforations or ports 31, through which live air is permitted to pass as long as the valve disk 22 is unseated, and consequently under normal conditions the hammer and feeding mechanism will receive the necessary live air.

A pin 32 may be provided to engage a perforation 33 formed in the stem 19, whereby the valve disk 22 may be positively held unseated, in an obvious manner.

35 What is claimed is:—

1. In a fluid operated drill, a cylinder, a chuck associated with the cylinder and having a groove formed therein, a hammer mov-

able in the cylinder, a tappet actuated by the hammer for striking a drill steel, a pneumatically operated feeding mechanism associated with the cylinder, a throttle valve associated with the cylinder for controlling the passage of air to the cylinder and feeding mechanism, a spring pressed valve disk, a shoulder associated with the valve disk, a rod having its lower end engaged with the shoulder to hold the valve disk in its inoperative position, a hook carried by the upper end of the rod and having its shank engaged in said groove to engage the tappet when the same moves upwardly, thereby shifting the rod to release the valve disk to permit the same to cut off the supply of air through the throttle valve, as and for the purpose set forth.

2. In a fluid operated drill, a cylinder, a hammer movable therein, a tappet operable by the hammer for striking a drill steel, a pneumatically operated feeding mechanism associated with the cylinder, a throttle valve for the cylinder for controlling the passage of fluid to the cylinder and feeding mechanism, a valve disk associated with the throttle valve adapted to seat thereon at times, means for normally holding the valve disk unseated, said means being operable by the tappet upon abnormal movement thereof to permit said valve disk to seat and cut off the supply of fluid to the throttle valve, and thus to the feeding mechanism, as and for the purpose set forth.

In testimony whereof I have hereunto set my hand.

LEO REVOR.
